BATHTUB SEAT ATTACHMENT

George B. Bentz, Bronx, N. Y.

Application August 5, 1938, Serial No. 223,334

7 Claims.

(Cl. 4—185)

The invention relates to a novel seat attachment for bathtubs, having a seat to extend transversely of a tub, and end members at the ends of said seat to abut the inner sides of the opposed tub walls, and the principal object of the invention is to provide a novel construction in which said seat and end members are unitarily connected by pivoted links which readily allow the seat to occupy either a raised or a lowered position.

Further objects are to provide either end members having supports to rest upon the tub rim, or end members having no such supports and adapted to wedge into position.

A still further object is to provide unusually simple and inexpensive, yet efficient and durable construction.

With the foregoing in view, the invention resides in the novel subject matter hereinafter described and claimed, description being accomplished by reference to the accompanying drawings.

Fig. 1 is an edge view of one form of the invention in raised position within a bathtub, the lowered position of the seat being shown in dotted lines.

Fig. 2 is a perspective view of the attachment shown in Fig. 1.

Fig. 3 is a view similar to Fig. 1 but illustrating a different form of construction.

Fig. 4 is a perspective view of the attachment shown in Fig. 3.

Fig. 5 is a view similar to Fig. 1 but showing a construction which wedges into operative position.

Fig. 6 is a perspective view of one end of the attachment shown in Fig. 5.

Fig. 7 is a view similar to Fig. 3 but showing a construction which wedges into the tub.

Fig. 8 is a perspective view of one end of the attachment shown in Fig. 7.

Fig. 9 is an edge view showing a still further form of construction in operative position, the seat being raised.

Fig. 10 is a perspective view of the attachment shown in Fig. 9 illustrating the seat lowered.

Fig. 11 is an edge view illustrating the manner in which the device of Figs. 9 and 10 may be folded into compact space when not in use.

Fig. 12 is a perspective view showing a still further form of construction.

In the drawings above briefly described, preferred details of construction have been illustrated, and while said details will be rather specifically explained, it is to be understood that vari-

ations may be made within the scope of the invention as claimed.

The forms of construction shown in Figs. 1 to 4 inclusive possess a number of features in common which may be described with the use of the same reference characters. Two U-shaped end frames 12 are provided to lie against the downwardly converging side walls 13 of a bathtub 14, the vertical side arms 15 of said frames being bent outwardly at their upper ends as shown at 16 to lie upon the tub rim. Preferably these supports 16 are connected by rods 17. Parallel vertical flanges 18 are welded or otherwise secured to the side arms 15 to project inwardly from the tub walls 13, said flanges being preferably of triangular shape in order that their inner edges may be vertically disposed. In the construction shown in Figs. 3 and 4, the inner edges of the flanges 18 are connected by upper and lower horizontal rods 19 and 20 respectively, but no such rods are employed in Figs. 1 and 2.

A seat 21 is provided to extend between the two end members or frames 12, and links 22 pivotally connect said seat with said end members or frames and permit said seat to occupy either a raised or a lowered position, said links being pivoted at 23 to the edges of the seat 21 and being pivoted at 24 to the flanges 18, in the present disclosure. In the construction shown in Figs. 3 and 4, the seat 21 rests upon the upper rods 19 when in raised position and upon the lower rods 20 when in lowered position, said rods relieving the links 22 of some of the weight of the seat and its occupant. In the construction shown in Figs. 1 and 2, however, the links carry this weight, said weight being transmitted to the tub rim by the end members 12 and their lateral supports 16, without causing any appreciable outward pressure upon the tub side walls 13, which pressure must often be avoided particularly if the tub be of relatively thin pressed metal construction. The construction shown in Figs. 3 and 4 also possesses these same advantages.

In Figs. 5 and 6, I have shown a construction identical with that of Figs. 1 and 2, except that no metal supports such as 16 are employed. In this form of the invention, the frames 12^a have their side arms 15^a connected directly by a rod 17^a, and the seat 21^a is pivoted to links 22^a which are pivotally connected with the flanges 18^a of said frames or end members 12^a. This form of construction wedges into operative position between the tub walls as will be clear from Fig. 5.

In Figs. 7 and 8, the end members or frames 12^b are identical with those shown in Figs. 5 and 6, 55

except that they are provided with upper and lower rods 19^a 20^a corresponding to the rods 19 and 20 above described and adapted to support the seat 21^b when the latter occupies its raised or lowered positions respectively, said seat being connected with the frames 12^b by links 22^b.

In Figs. 9, 10 and 11, I have shown a construction which may well be constructed from wood if desired, with the exception of the links 22^c and 10 their pivots 23^c and 24^c. The end members 12^c 15 are of wedge-like form to lie against the tub side walls, the inner faces 18^c of said end members being disposed in downwardly converging relation when the device is operatively positioned. The seat 21^c is provided with beveled ends 21' to abut the faces 18^c when the seat is moved either to the raised position of Fig. 9 or to the lowered position of Fig. 10. This form of construction is intended to wedge tightly into the tub, and the end members 12^c 20 are preferably provided with ribbed rubber strips 12' to anti-slippingly abut the tub. When the device is not in use, it may be compactly folded as seen in Fig. 11, which is of advantage in the stockrooms of the factory or the retailer, or in 25 the home, being of particular advantage when the devices are to be placed in cartons and delivered by mail order houses.

In the form shown in Figs. 9, 10 and 11, due to the fact that the tub side walls crowd the end 30 members 12^c inwardly into tight frictional contact with the beveled ends 21' of the seat 21^c, the links 22^c are called upon to support very little weight and may therefore be of light construction to act primarily as means for unitarily connecting 35 the end members and seat and for guiding them when adjustments are being made to position said seat at a raised or a lowered position.

In Fig. 12, an end frame 12^d and a seat 21^d are connected by pivoted links 22^d, each formed of 40 overlapped sections adjustably secured together by a bolt-and-slot-connection 22^e. By adjusting the length of the links 22^d, the seat may be supported at different heights whether occupying a raised or a lowered position.

From the foregoing, taken in connection with 45 the accompanying drawings, it will be seen that novel and advantageous provision has been made for carrying out the objects of the invention, and attention is again invited to the possibility of making variations within the scope of the invention as 50 claimed. For example, in the form shown in Figs. 10 and 11, the ends 21' of the seat may be rounded instead of beveled and seated in half-round upper and lower grooves formed in the opposed faces 18^c 55 of the end members 12^c.

I claim:

1. A seat attachment for a bathtub, comprising 60 two end members to engage the inner sides of the opposed walls of a tub, said end members having upper seat-engaging portions and lower seat-engaging portions, a seat to extend between said end members, and links pivoted at one end to said end members and at the other end to said seat, said links being swingable to raised and lowered 65 positions to allow vertical adjustment of the seat into engagement with said upper or said lower seat-engaging portions.

2. A seat attachment for a bathtub, comprising

two end members to abut the inner sides of the opposed walls of a tub, a seat to extend between said end members, and links pivoted to said end members and to said seat and swingable to raised and lowered positions to allow vertical adjustment of the seat to a raised or a lowered position, said end members being provided with upper and lower supports upon which the ends of the seat rest when said seat occupies said raised and lowered positions respectively. 5

3. A seat attachment for a bathtub, comprising 10 two end members to abut the inner sides of the opposed walls of a tub, a seat to extend between said end members, and links pivoted to said end members and to said seat and swingable to raised and lowered 15 positions to allow vertical adjustment of the seat to a raised or a lowered position, said end members having lateral supports at their upper ends to rest upon the tub rim.

4. A seat attachment for a bathtub, comprising 20 two U-shaped frames to lie against the inner sides of the opposed walls of a tub, the vertical side arms of said U-shaped frames being provided with parallel vertical flanges to project inwardly from the tub walls, a seat to extend between said side 25 frames, and links pivoted to said seat and to said flanges and swingable to raised and lowered positions to allow vertical adjustment of the seat to a raised or a lowered position.

5. A seat attachment for a bathtub, comprising 30 two U-shaped frames to lie against the inner sides of the opposed walls of a tub, the vertical side arms of said U-shaped frames being provided with parallel vertical flanges to project inwardly from the tub walls, a seat to extend between said side 35 frames, links pivoted to said seat and to said flanges and swingable to raised and lowered positions to allow vertical adjustment of the seat to a raised or a lowered position, and upper and lower horizontal rods secured to said flanges of each end 40 frame to support the seat in said raised or lowered position respectively.

6. A seat attachment for a bathtub, comprising 45 two U-shaped frames to lie against the inner sides of the opposed walls of a tub, the vertical side arms of said U-shaped frames being provided with parallel vertical flanges to project inwardly from the tub walls, the upper ends of said side arms being bent laterally outward to rest upon the tub 50 rim, a seat to extend between said side frames, and links pivoted to said seat and to said flanges and swingable to raised and lowered positions to allow vertical adjustment of the seat to a raised or a lowered position.

7. A seat attachment for a bathtub, comprising 55 two end members to abut the downwardly converging sides of the opposed walls of a tub, said end members having inner faces which converge downwardly when said members are in operative position, a seat to extend between said end members and having beveled ends to abut said inner faces thereof when said seat occupies either a raised or a lowered position, and links pivoted to said seat and to said end members, said links being vertically swingable to allow said seat to occupy 60 either said raised or said lowered position.

GEORGE B. BENTZ.
